UNITED STATES PATENT OFFICE.

SIDNEY M. BARNARD, OF FORESTVILLE, CONNECTICUT.

CASE FOR SHIPPING CANS OF ICE-CREAM.

1,147,291.

Specification of Letters Patent. Patented July 20, 1915.

Application filed July 1, 1911. Serial No. 636,457.

To all whom it may concern:

Be it known that I, SIDNEY M. BARNARD, a citizen of the United States, and a resident of Forestville, in the county of Hartford, and State of Connecticut, have invented a new and Improved Case for Shipping Cans of Ice-Cream, of which the following is a specification.

My invention relates to the class of devices above named, and an object of the invention among others is to provide a device of this class in which the cans may be kept at substantially an even temperature whereby the cream is maintained in a solid condition and which protects the cans from injury.

A further object of the invention is to provide a device of this class with which the cans may be readily handled and from which they may be taken with little trouble.

One form of case embodying my invention and in the construction and use of which the objects hereinabove set out may be attained is illustrated in the accompanying drawings in which—

Figure 1 is a view in side elevation of a case embodying my invention with the fastenings partially undone. Fig. 2 is a top view of the same. Fig. 3 is a view in vertical central section.

In the shipment of ice cream to supply the demand created at the present time, it becomes of importance to provide means whereby the cans may be readily handled and protected from injury, that shall occupy a minimum amount of space during such shipment, and it is of utmost importance that the temperature of the can shall be kept even, so that the cream will be maintained in a solid condition for a maximum length of time. Heretofore, it has been a common practice to pack the cans with ice and salt in tubs, this involving much work in packing the cans, and the package occupying a great amount of space, and in the return shipment of the cans two packages must be returned.

The case including a jacket 6 illustrated in the accompanying drawings obviates these objections which case is made of flexible material having qualities that cause a slow conductivity of heat. In the preferred form of construction this jacket includes two layers of canvas or like material, an outer layer 7 and an inner layer 8. A filling 9 is located between the outer and inner layers this filling preferably consisting of cow hair felt which I have found after repeated experi-

ments to possess satisfactory qualities as a heat insulator. These three layers, the outer and inner layers and the filling of cow hair felt are stitched together or quilted as by 60 rows of stitches 10 extending both lengthwise and crosswise of the jacket.

A bottom 11 of a comparatively stiff material closes one end of the jacket, the edge of which is secured to the edge of this bottom in any suitable manner. In the form of construction herein shown this bottom is formed of wood, although a less stiff material may be employed if desired. Nails 12 are shown as a means of securing the jacket 70 to the bottom. The lower edge of the jacket is thus attached for the greater portion of the distance around the bottom, a portion 13, however, being left unattached to the edge, so that the jacket may be turned backward 75 at this point. A cap 14 of a construction similar to the bottom is secured at the opposite end of the jacket and this is secured except for a portion 15 which is left unattached so that the jacket may be folded back 80 to permit removal of the can through the side of the case.

Supporting straps 16 extend around the jacket at suitable intervals being secured thereto at different points. These straps are 85 provided with any suitable fastening means as buckles 17, which fastenings terminate at such distance from one side edge of the jacket as to provide an overlapped portion 18. The opposite edge of the jacket, bearing the buckles overlies the overlapped portion and the straps are then fastened to hold the flap secure. A cross piece 21 is secured to the cap 14, extending preferably thereacross to strengthen it and a handle 19 may 95 be secured to the cap as a means for carrying the case. In the construction herein shown the handle is secured to this cross piece.

The case is made of a size to closely fit the 100 can to be contained therein so that it is but little larger in size than said can. The jacket not only preserves the can from the effects of radiation of heat but also forms a cushion to prevent indentation of the cans 105 by contact with each other or with other objects, and in reshipment the cans are placed within the jackets and are thus protected. The straps 20 need not extend entirely around the top and bottom but may be secured at a suitable distance from each meeting edge of the jacket to serve as a rein- 110

forcement for the fastenings that secure the edges of the jacket and especially at these edges where the strain is particularly severe.

While I have shown herein one form of device embodying my invention, this construction may be departed from to a greater or lesser extent and yet be within the spirit and intent of the invention, which I, therefore, do not limit to a structure made in exact accordance with that herein shown and described.

I claim.

- 5 1. A packing case for ice-cream cans including a jacket of flexible material to closely fit the can, a bottom of rigid material of a size substantially equal to the cross sectional area of a can, means for securing one end of the jacket to the bottom for substantially the entire distance therearound, a 10 top of rigid material, means for securing the opposite end of the jacket to the top leaving an unsecured flap sufficient to permit removal of the can through the opening, and means for closing the opening.
- 15 2. A packing case for ice-cream cans in-

cluding a jacket of flexible material, a top and bottom of rigid material of a size substantially equal to the cross sectional area of a can, means for securing the ends of the jacket to the top and bottom, one end being left unattached for a distance sufficient to permit removal of a can through the opening, and means for securing the edges of the jacket.

3. A packing case for ice-cream cans including a jacket of flexible material, heads of rigid material and of a size substantially equal to the cross sectional area of a can secured to each end of the jacket, one end of the jacket being left unsecured for a sufficient distance to permit removal of the can through the opening, a cross piece of stiffening material extending across one of the heads, and a handle secured to said cross piece.

SIDNEY M. BARNARD.
